HAND-CARRIED RECEPTACLE

Robert T. Haubrick, Fort Monmouth, N. J.

Application March 19, 1947, Serial No. 735,657

1 Claim. (Cl. 150—46)

1

This invention relates to ladies' handbags and more specifically to an improved type of handbag having a cosmetics container conveniently available as a permanent and functional part thereof.

Heretofore, ladies' handbags have served as a means for carrying numerous small items and have become a conventional part of the feminine attire. In addition to its utilitarian value as a containing and carrying means, the lady's handbag serves as an ornamental element of women's costuming.

In the past, however, it has proven inconvenient and manually difficult for a woman to procure her cosmetics compact from among other items in her handbag and apply the cosmetics without laying the handbag down. If no convenient resting place is available, the handbag must usually be held under the arm. Such action is uncomfortable and tiring. Furthermore, the handkerchief or other often-needed contents in the handbag are not easily gotten while hands are occupied with the use of the compact.

In view of these difficulties, a specific object of the present invention is to provide a lady's accessory bag which functions as a handbag and at the same time provides a conveniently available cosmetics compact.

A further object is to provide an accessory bag having a compact so coupled thereto that it cannot be lost or temporarily mislaid.

A still further object is to provide an accessory bag having as its cover, a cosmetics compact.

Another object of the present invention is to provide a lady's handbag with a cosmetics compact forming the cover thereof, whereby a mirror contained within the compact can conveniently be of substantially larger dimensions than usual without introducing additional bulk or carrying difficulty.

A further object is to provide a handbag and cosmetics compact combined so that they are both easily held while the compact is in use.

An additional object is to provide a handbag and cosmetics compact, in combination, which so cooperate that the contents of the handbag are conveniently available while the compact is in use.

These and further objects are achieved by apparatus of the present invention which is described in detail in the following specification and shown in the drawing in which:

Fig. 1 is a perspective view of a preferred embodiment of the present invention;

Fig. 2 is a second perspective view of the em-

2

bodiment of Fig. 1 showing the cosmetics compact and handbag in position for simultaneous use;

Fig. 3 shows in perspective a further embodiment of the present invention; and

Fig. 4 is a partial view of a further embodiment of this invention, a portion thereof being cut away to demonstrate a possible coupling means of the invention, and a phantom view being included to show one of the positions of elements of the invention.

With reference to the accompanying drawing and more specifically to Fig. 1, a lady's accessory bag is shown having a receptacle 11 with a substantially circular opening (reference 23 of Fig. 2) in the top thereof. About the periphery of this opening a rigid supporting ring 12 is secured. A cosmetics container 13 of the well known compact variety comprising a lid 20 and bottom 21 joined by hinge 22 is movably attached to the supporting ring 12 by pin 14 so as to form a cover for the receptacle 11 when in the position shown in Fig. 1. Two protruding ears 15 and 16 may be formed in container 13 and supporting ring 12 respectively to receive coupling pin 14. Further attention will be devoted later to possible coupling structures.

For carrying convenience a strap 17, long enough to be slipped over the arm, is attached to the receptacle 11 at two diametrically opposed points by means of conventional ring-shaped wire members 18 (only one shown). Members 18 are in turn secured to receptacle 11. It is apparent that strap 17 may be attached to either receptacle 11 as shown or to supporting ring 12, and that any number of well known means may be used to properly secure the two ends of said strap 17.

The receptacle 11 may be made of flexible material such as fabric, soft leather, plastic, etc., or may be formed to rigid shape out of a variety of relatively inflexible materials. An additional opening formed by a slide fastener 19 may be disposed in receptacle 11 to allow easier entry and for cleaning purposes, if desired. Such ornamental trim as initials 24 may be attached to a conspicuous portion of container 11.

The cosmetics container 13 may be one of any variety of well-known ladies' grooming kits. The contents of these often include rouge, powder, powder puff, mirror, etc., and the containers commonly have separate compartments for these various contents. As shown in the drawing, the cosmetics container 13 is disk-shaped, having circular symmetry. It will be apparent to one versed in the art that container 13 may be any

of a variety of shapes such as oval, rectangular, etc., with the supporting ring 12, the opening 23 of the container 11 and possibly the container 11 itself, formed to similar shape so as to conform attractively with their cover member, cosmetics container 13. It is further apparent that container 13 is not limited in use to cosmetics carriage but may be adapted to carry keys, comb, lipstick, handkerchief and other such common feminine items, with container 13 adapted to receive the desired items in a manner common to the art.

In Fig. 2 is shown the same structure of Fig. 1, with both receptacle 11 and cosmetics container 13 open for simultaneous use. The opening 23 to receptacle 11 is apparent in this figure, with supporting ring 12 secured about the periphery thereof. The means by which receptacle 11 is so secured to ring 12 is not herein shown, but may be by any well known means such as cementing, riveting, moulding within plastic, etc. Elements 31 and 32 form a catch mechanism for securing lid 20 to container bottom 21 when the compact 13 is in the closed position. A wide variety of catch mechanisms are known in the art and may be here employed.

A possible form of cosmetics container 13 is shown with lid 20 and bottom 21 joined by hinge 22. A large viewing mirror 30 forms an integral portion of the lid 20, and a circular partition 33, which carries rouge spot 35 and applicator 36, is movably joined to container bottom 21 by hinge 34. By raising partition 33 on the provided hinge 34, a powder puff and supply of powder (neither shown) contained in bottom 21 are made available for use. It can be realized from this figure that a very large viewing mirror 30 can be carried in the lid of the spacious container 13 without requiring any of the valuable space of receptacle 11. Such a large mirror adds much in the way of ease of viewing.

The apparatus of this invention can easily be transformed from the arrangement of components for carrying, as in Fig. 1, to their arrangement for use, as shown in Fig. 2. This action merely involves the pivoting of container 13 with respect to supporting ring 12 about pin 14 and opening the container 13 in a conventional manner. With the elements of the apparatus of this invention in the position shown in Fig. 2, the entire structure may be easily supported by one hand, leaving the other hand free to use the cosmetics in container 13 or to procure any desired items from receptacle 11. It is apparent that the cosmetics of container 13 may be used, if desired, with the container 13 in the normal carrying position shown in Fig. 1, but with lid 20 raised.

A variety of means may be employed to join the cosmetics container 13 to the supporting ring 12 without departing from the scope of the invention. One such means, differing from that of Figs. 1 and 2, is illustrated in Fig. 3. In this figure, the receptacle 11' is shown having supporting ring 12' secured about the periphery of the opening in the receptacle. The cosmetics container 13' forms a functional part of the structure and comprises a lid 20' and a bottom 21' joined by hinge 22'.

The point of distinction between this and the previously cited structure rests in the use of a second hinge 40 to couple the cosmetics container 13' to the supporting ring 12'. By such coupling means, the cosmetics container 13' and receptacle 11' can be easily held open simulta-

neously as illustrated, thus permitting enjoyment of the many advantages described above.

With the container 13' held closed by any of a variety of well known catch mechanisms, the container may be swung on hinge 40 through a turn of approximately 180 degrees and thus made to form, by cooperative agreement with supporting ring 12', a cover for the receptacle 11'. Further catch means may be provided to hold container 13' and supporting ring 12' in this adjacent relationship, thus maintaining the apparatus of Fig. 3 in a closed or carrying position.

In Figs. 1 and 2, the apparatus of the invention is provided with a simple flexible strap 17 for holding and carrying convenience. A possible alternate carrying means is illustrated in Fig. 3 and comprises two rings 41 formed of substantially rigid material and secured to the receptacle structure at diametrically opposed points. Handle straps 42 (one shown) may be provided on either side of the receptacle 11 as additional grasping means.

In Figs. 1 and 2, the desired pivotal relationship between the supporting ring 12 and cosmetics container 13 is maintained by pin 14. In addition to so maintaining elements 12 and 13, the coupling structure associated therewith may also be adapted to secure them in desired relative positions, such as the open or closed positions. A possible coupling means for achieving this end is illustrated in Fig. 4.

Referring to Fig. 4, the cosmetics container 13 is shown comprising a lid 20 and a bottom 21 movably attached to one another by hinge 22. Protruding ears 15 and 16 are formed in the compact 13 and supporting ring 12 respectively and are adapted to receive the coupling structure shown in detail. A portion of the receptacle 11 which is fixedly joined to supporting ring 12 is shown.

To provide the desired pivotal relationship between the cosmetics container 13 and the supporting ring 12, a pin 50 engages said members 13 and 12 in the central region of their respective protruding ears. The pin 50 passes through the ears 15 and 16 with its central axis perpendicular to the adjacent plane faces 52 and 53 of said ears, and is further adapted to permit the container 13 to be rotated about pin 50 into a desired position, such as that shown in Fig. 2. To maintain the ears 15 and 16 in a smooth and adjacent cooperative relationship, the recess in ear 16 which receives one head of the pin 50 is enlarged to hold helical spring 51. This spring 51 is wound about pin 50 and held under tension in the restriction between one head of pin 50 and the base of the recess of ear 16.

Disposed in the surface 52 of ear 16 are recesses numbered 54 through 59 which are shaped and located to receive the protrudances 60 and 61, formed in the surface 53 of the ear 15, when the members of the apparatus are in certain positions of rotation. For example, when the apparatus of the invention is in the closed or carrying position as shown in Fig. 1 (and by the solid lines of Fig. 4), the protrudances 60 and 61 are seated in recesses 58 and 59 respectively, and are held in such seated relationship by the tension of spring 51, thereby effectively locking the carrying receptacle and maintaining its contents safely within.

To place the apparatus described in the open position with the contents of the receptacle 11 available for use (such as is shown in Fig. 2),

the cosmetics container 13 is pivoted about the pin 50 into the phantom position 70 of Fig. 4. Sufficient freedom is provided by the helical spring 51 to permit the protrudances 60 and 61 to be unseated from the recesses 58 and 59, and when the container 13 arrives in the phantom position these protrudances fall into recesses 54 and 55 respectively. The apparatus is thereby secured in the open position for the convenience of the user. Should it be desired to open the receptacle by a counter-clockwise rather than clockwise rotation of the compact 13, the recesses 56 and 57 will serve to receive the protrudances 60 and 61 respectively and thereby hold the elements of the invention in this open position.

The invention described in the foregoing specification need not be limited to the details shown, which are considered to be illustrative of one form the invention may take. What I desire to secure by Letters Patent and claim is:

A lady's handbag comprising a first receptacle of substantially flexible material, said first receptacle having a restricted and substantially circular opening therein, a rigid supporting ring having a diameter approximately equal to that of said circular opening being fixedly attached to said first receptacle about the periphery of said circular opening therein, a second receptacle rigidly formed and substantially disk-shaped having a diameter approximately equal to the outer diameter of said supporting ring, a coupling member associated with said second receptacle and said supporting ring at their respective outer peripheries, said coupling member being adapted to maintain said second receptacle and said supporting ring in sliding adjacency, said coupling

member having an associated spring means adapted to provide tension for maintaining said second receptacle and said supporting ring in adjacency, a plurality of small protrudances and a multiplicity of recesses shaped to receive said protrudances being disposed in opposed and adjacent faces of said second receptacle and said supporting ring, said protrudances and said recesses being so mutually aligned that said protrudances seat in recesses when said second receptacle and said supporting ring are in predetermined relative positions, said spring means providing sufficient flexibility to permit said protrudances to be unseated when a different relative position is desired, whereby said protrudances and said recesses cooperate to temporarily secure said first and said second receptacles in certain convenient relative positions for use.

ROBERT T. HAUBRICK.
